NOZZLE FOR FIRE EXTINGUISHING
APPARATUS

Walter S. Diehl, United States Navy

Application December 5, 1935, Serial No. 52,978

7 Claims. (Cl. 169—11)

(Granted under the act of March 3, 1883, as
amended April 30, 1928; 370 O. G. 757)

The present invention relates to fire extinguishing apparatus and has a particular relation to nozzles for projecting a stream of flame smothering fluid, such as carbon dioxide, upon the area of conflagration.

The principal object of the present invention is the provision of a nozzle for a fire extinguishing apparatus that is capable of projecting a stream or jet of a fire extinguishing medium surrounded by an air excluding envelope or blanket of a similar or different medium at a greater range and in a more concentrated form than by nozzles heretofore designed.

Another object of the invention is the provision of a nozzle of the character described that is adapted to project a main stream of fire extinguishing fluid upon a zone of combustion at a relatively high velocity and to discharge simultaneously an auxiliary stream of air excluding mediums surrounding said main stream and at a reduced velocity.

A further object of the invention is the provision of a nozzle of the type referred to in which the surrounding or auxiliary stream is projected positively under pressure and without the danger of drawing air into the nozzle or of entraining air in the main stream.

With these and other objects in view, as well as other advantages that may be incident to the use of the improvements, the invention consists in the parts and combinations thereof herein-after set forth and claimed, with the understanding that the several necessary elements constituting the same may be varied in proportion and arrangement without departing from the nature and scope of the invention, as defined in the appended claims.

In order to make the invention more clearly understood, there are shown in the accompanying drawings, means for carrying the invention into practical effect, without limiting the improvements in their useful application to the particular construction, which, for the purpose of explanation, have been made the subject of illustration.

In the accompanying drawings:

Fig. 1 is a longitudinal sectional view through a nozzle constructed in accordance with the invention;

Fig. 2 is a vertical transverse sectional view taken on line 2—2 of Fig. 1;

Fig. 3 is a similar view taken on line 3—3 of Fig. 1;

Fig. 4 is a longitudinal sectional view through

another form of nozzle embodying the invention; and

Figs. 5, 6 and 7 are diagrammatic views illustrating paths of flow of the fire extinguishing medium in different forms of nozzles, all constructed in accordance with the invention.

Referring to the drawings and particularly to Figs. 1 to 3 thereof, a fire extinguishing nozzle embodying the invention is shown as comprising a cylindrical base member 10 having an internally and externally screw-threaded nipple portion 11 of a reduced cross section adapted to be screwed onto the end of a pipe connection 12 communicating with a reservoir, not shown, containing a fire extinguishing fluid under pressure. 15 A circular plate 13 formed with a circumferential flange 14 is mounted on the nipple portion 11 in abutting relation to the rear face of the base 10, and is maintained against displacement therefrom by a lock nut 15 threaded onto the nipple 20 portion 11. Suitably secured to the outer cylindrical surface of the base member 10, such as by solder or the like, and extending forwardly therefrom is a tubular member 16 of frusto-conical shape arranged with its smallest end outermost. 25 Similarly secured to the inner surface of the flange 14 is a forwardly extending tubular member 17 of cylindrical shape, the members 16 and 17 being maintained in concentric spaced relation by a bracket member or spider 18 secured to the 30 latter.

The base member 10 is also formed with a centrally disposed rearwardly flared chamber 19 which communicates with the interior of the tubular member 16 through an orifice 20 of reduced area, and also with the space between the members 16 and 17 through a plurality of radially extending forwardly inclined passageways 21. A screen 22 may be provided within the chamber 19 if so desired, in order to break up or disintegrate 40 relatively large particles of solid carbon dioxide in the stream which might otherwise lodge in and obstruct the orifice 20.

In this particular construction the main stream of fire extinguishing fluid flows and is projected 45 from the central tubular member 16 at a relatively high velocity, but a certain and lesser amount of said fluid escapes laterally through the passages 21 into the space between the inner member and the outer member through which it 50 flows at a somewhat reduced velocity and emerges therefrom in a cylindrical stream auxiliary surrounding the main stream or jet and prevents the entrainment of air by said main jet.

In Fig. 4 there is shown another form of the invention in which the improved nozzle comprises an internally and externally screw-threaded nipple 23 adapted to be threaded onto the end of the pipe connection 12. A cap 24 formed with a chamber 25 and an outlet port or orifice 26 therein is threaded on the forward end of the nipple 23 and may also be provided with a screen 27, the edges of which are clamped between the cap 24 and the end of the nipple 23. A circular plate 28 formed with a circumferential flange 29 is mounted on the nipple 23 in abutting relation to the rear face of the cap 24 and secured in position by a lock nut 30 also threaded onto the nipple 23. In this particular construction the rear end of the outer tubular member 31, which is of frusto-conical shape as before, is suitably secured within the flange 29 of the plate 28 and converges outwardly, as shown. The outer tubular member 32 is also of frusto-conical shape reversed with respect to the angle of convergence of the inner member 31 so that its inner end engages and is secured to the inner member 31 at a point where the diameters of the two members are substantially the same, which in the present case is about midway the length of the inner member. This provides an annular space 33 surrounding the inner member 31 of increasing area outwardly which communicates with the interior of the inner member through a plurality of circumferentially spaced ports 34. These ports are located well to the rear end of the space 33 so that the fluid flowing through these ports does not produce a zone of rarefied atmosphere within this space.

The operation of this form of the invention is substantially the same as that shown in Figs. 1 to 3, the difference being mostly one of structure.

In Fig. 5 still another form of nozzle embodying the invention is shown. In this case the inner tubular member 35 is flared outwardly and its wall is struck inwardly at intervals so as to provide a plurality of ports 36 having inwardly projecting louvers 37. These louvers positively deflect a portion of the fluid flowing through the member 35 in an outward and forward direction so as to provide a protecting envelope of relatively slowly moving fluid surrounding the main stream projected from the member 35, this envelope being approximately defined by the broken line 38.

In Fig. 6 there is illustrated a construction substantially like that shown in Fig. 5, except that the inner member 39 is of cylindrical shape. This member 39 is formed with ports 40 and louvers 41 for deflecting a portion of the fluid outwardly to form an envelope of slow moving fluid defined by the broken line 42.

In Fig. 7 a construction is shown in which the inner tubular member 43 is generally of cylindrical shape but formed with inwardly converging outer edges 44. In this case a portion of the fluid from a supply pipe 45 escapes from the flared end 46 of the pipe around the rear end of the member 43, so as to provide an air excluding envelope defined by the broken line 47. It will be understood, however, that the member 43 may be outwardly flared, as in Fig. 5, or in cylindrical shape throughout, as in Fig. 4, if desired. The member 43 is carried by a stem 48 which is threaded into a spider 48 fixed within the supply pipe 45. This permits the member 43 to be adjusted relative to the pipe 45 so as to vary the size of the discharge orifice therebetween. In all of the nozzle structures hereinabove described the air excluding envelope of slow moving fluid will eventually be entrained by the main or central

jet or stream, but the parts are so proportioned and designed that this will not occur completely until the area of conflagration is reached by the fire extinguishing medium. By thus providing an outer zone of gaseous fluid which will not support or aid combustion, the fluid of this zone is entrained by the main jet issuing from the nozzle instead of air, as would ordinarily be the case.

If desired, the outer tubular members shown in the several figures may be formed with outwardly flared or bell-shaped forward ends so as to disperse the fluid laterally to some extent and increase the depth of the envelope of air excluding medium.

Other modifications and changes in the proportions and arrangement of the parts constituting the invention may be made by those skilled in the art without departing from the nature and scope of the invention, as defined in the appended claims.

The invention described herein may be manufactured and used by or for the Government of the United States of America for governmental purposes without the payment of any royalties thereon or therefor.

I claim:

1. A fire extinguishing apparatus comprising in combination a source of gaseous fire extinguishing medium under pressure, an inner tubular member adapted to be communicably connected with said source of fire extinguishing medium for projecting a main jet of said medium, and an outer tubular member having a flared outer end surrounding the rear end of said inner tubular member in spaced relation thereto and forming therewith an annular passage increasing in cross sectional area uniformly throughout its length toward the outlet end thereof and also communicable with said source of fire extinguishing medium for discharging said medium in an unconfined stream moving at a lower velocity than and closely surrounding said inner tubular member and said main jet, thus to minimize the entrainment of air by said main jet, said inner member being adjustable relative to said outer member to vary the size of said passage and the stream projected therethrough.

2. A fire extinguishing apparatus comprising in combination a source of gaseous fire extinguishing medium under pressure, an inner tubular member adapted to be communicably connected with said source of fire extinguishing medium for projecting a main jet of said medium, and an outer tubular member surrounding the inner tubular member in spaced relation thereto and forming therewith an annular passage at the rear end thereof also communicable with said source of fire extinguishing medium and increasing in cross sectional area uniformly throughout its length toward the outlet end thereof for discharging said medium in a stream moving at a lower velocity than and closely surrounding said inner tubular member and said main jet, thus to minimize the entrainment of air by said main jet, said inner and outer members being adjustable relative to each other to vary the size of said passage and the stream projected therethrough.

3. A fire extinguishing apparatus comprising in combination a source of gaseous fire extinguishing medium under pressure, an outer tubular member adapted to be communicably connected with said source of fire extinguishing medium, a second tubular member, means to mount said second tubular member within said outer

5 tubular member in a manner to provide an annular passage therebetween including means to adjust said outer and second members relative to each other to vary the size of said passage and the stream projected therethrough, and means to establish communication between said second tubular member and said source of fire extinguishing medium for projecting a main jet of said medium, said passage increasing in cross sectional area uniformly throughout its length to 10 ward the outlet end thereof, and serving to discharge said medium in a stream moving at a lower velocity than and closely surrounding said second tubular member and said main jet, thus to minimize the entrainment of air by said main jet.

15 4. A nozzle for a fire extinguishing apparatus comprising an inner tubular member adapted to be communicably connected with a receptacle 20 containing a supply of fire extinguishing fluid under pressure and converging in an outward direction for projecting a main jet of said fluid, and an outer tubular member surrounding said inner tubular member in spaced relation thereto 25 and converging in an inward direction to a point intermediate the ends of said inner member to form an outer annular passage also communicable with said receptacle and increasing in cross sectional area uniformly throughout its length 30 toward the outlet end thereof for discharging said fluid in a stream moving at a lower velocity than and closely surrounding said main jet, thus to minimize the entrainment of air by said main jet.

35 5. A nozzle for a fire extinguishing apparatus comprising an inwardly flared frustro-conical inner tubular member adapted to be communicably connected with a receptacle containing a supply of fire extinguishing fluid under pressure for projecting a main jet of said fluid, and an outwardly flared frustro-conical outer tubular member surrounding said inner tubular member in spaced 40 relation thereto, the rear end of said outer member terminating intermediate the ends of said inner member, the walls of said members defin-

ing an annular passage communicable with said receptacle and increasing in cross sectional area uniformly throughout its length toward the outlet end thereof for discharging said fluid in a stream moving at a lower velocity than and closely surrounding said main jet, thus to minimize the entrainment of air by said main jet.

5 6. A nozzle for a fire extinguishing apparatus comprising an inwardly flared frustro-conical inner tubular member adapted to be communicably connected with a receptacle containing a supply of fire extinguishing fluid under pressure for projecting a main jet of said fluid, and an outwardly flared frustro-conical outer tubular member surrounding said inner tubular member in spaced relation thereto, the rear end of said outer member terminating intermediate the ends of said inner member, the walls of said members defining an annular passage communicable with said inner member rearwardly of the discharge 10 end of said inner member, and increasing in cross sectional area uniformly throughout its length toward the outlet end thereof for discharging said fluid in a stream moving at a lower velocity than and closely surrounding said main 15 jet, thus to minimize the entrainment of air by said main jet.

20 7. A nozzle for a fire extinguishing apparatus comprising an inner tubular member adapted to be communicably connected with a receptacle 25 containing a supply of fire extinguishing fluid under pressure for projecting a main stream of said fluid; and an outer tubular member surrounding said inner tubular member in spaced relation thereto, the walls of said members being 30 inclined in an axial direction relative to one another and defining a passage also communicable with said receptacle and increasing in cross sectional area throughout its length toward the outlet end thereof, for discharging said fluid 35 in a cylindrical stream moving at a lower velocity than and closely surrounding said main stream, thus to minimize the entrainment of air by said main stream.

WALTER S. DIEHL.
